UNITED STATES PATENT OFFICE.

ERNST WILLY SCHUSTER, OF CHICAGO, ILLINOIS.

STEAM-MOTOR.

1,231,207.

Specification of Letters Patent. Patented June 26, 1917.

Application filed February 3, 1917. Serial No. 146,424.

To all whom it may concern:

Be it known that I, ERNST W. SCHUSTER, a citizen of the United States, resident of Chicago, in the county of Cook and State of

Illinois, have made a certain new and useful Invention in Steam-Motors; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 Figure 1 is a side view of the invention, partly in section on the line 1—1, Fig. 2.

Fig. 2 is a plan view of the invention partly in section on the line 2—2, Fig. 1.

The invention has relation to steam motors or engines, having for its object to provide an improved rotary motor which will utilize the waste or exhaust steam and provide a maximum power for a minimum expenditure of steam and fuel.

25 The invention consists in the novel construction and combinations of parts, as hereinafter set forth.

In the accompanying drawings, illustrating the invention, the numeral 2 designates 30 a boiler or drum having suitable means for converting the water contained therein into steam, said means consisting preferably of wires 3, surrounding the boiler in the shell thereof and heated by an electric battery 4, 35 said drum being suitably insulated, as by asbestos layer 5 and vacuum space 6.

7 is the motor, consisting of a rotary wheel mounted upon a shaft 8, said wheel running within an outer stationary casing or cylinder 9, provided with end heads 10, 10, bolted thereto at 11. The motor wheel is provided in its circumferential portion with a plurality of radial blades 12, having intervening radial spaces 13, and tightener or packing rings 14 are provided at the ends of the casing, at the corners between the end heads and the cylinder.

Mounted upon the outside of the stationary cylinder are longitudinal pipes 15, 16, 50 17, 18 and 19, usually five in number, equally spaced apart from each other around the cylinder, the bores of said pipes forming chambers 15', 16', 17', 18' and 19', to which the steam is delivered, and communicating respectively with said chambers, and delivering the steam to the blades of the motor

wheel, are a plurality of pipes or conduits 20, 21, 22, 23 and 24, there being one series of said conduits for each of the steam chambers.

60

The steam is delivered from the steam drum of the boiler through pipes 25 to the first steam chamber 15', and through the delivery conduits 20, the steam impinging against the radial blades of the motor wheel 65 within the spaces between the blades, and usually at about right-angles or a little more than right-angles to said blades. The steam will be delivered in jets from the first series of conduits to the radial blades, and will 70 thereby cause the wheel to rotate to a definite degree, the blades coming consecutively into register with the delivery conduits, and the steam delivered to the blades being, as the blades pass out of register with the conduits, confined within the radial spaces, 75 which are closed at the bottom and sides and open at their outer ends.

The wheel being rotated as stated, the radial spaces, with the steam confined therein at high pressure, will next come into register with pipes 26, and be thereby conveyed outwardly to the next or second steam chamber 16', from which the steam will be delivered, through pipes 21, to the wheel blades 80 85 in the same way as first stated, except that in this case the expansive force of the steam under high pressure is relied upon for the forcible action of the steam upon said blades, there being no communication of the steam 90 chamber 16' with the steam drum of the boiler.

The wheel will in this way be caused to rotate further to a definite degree, the steam, still under high pressure, somewhat reduced, 95 being confined within the radial spaces, which will next come into register with the pipes 27, and be thereby conveyed outwardly to the steam chamber 17', next in order, from which the steam will be delivered as 100 stated again to the radial blades through pipes 22, to cause the wheel to rotate further. This operation being continued, the steam will be delivered in turn to the steam chambers 18' and 19', through pipes 28 and 29, 105 and from said chambers, through delivery conduits 23 and 24, to the radial blades in the same way as stated for the delivery to said blades from the pipes 27. In this manner the steam will be delivered intermittently from the steam drum to the radial blades at one portion of the wheel, and si- 110

multaneously and also intermittently to the radial blades at different locations entirely around the motor wheel, which will thereby be effectually and powerfully rotated.

5 From the radial spaces last in order the steam is delivered through pipe 30 to the radial blades 31 of an auxiliary motor wheel 32, operating a pump 32' or other suitable engine and having a stationary casing 33, 10 serving to confine the steam within the radial spaces 34 between said blades, as the blades pass out of register with the delivery end of the pipe 30, the confined steam, under reduced pressure, being delivered successively from said radial spaces to a pipe 35 15 leading to a feed water tank 36, said tank having a discharge pipe 37 to the boiler.

The steam pressure is utilized fully before the steam is discharged into the feed water 20 tank, and will effectually and powerfully rotate the motor with a minimum expenditure of steam and fuel. The auxiliary motor may be used or not, as desired, and the number of steam chambers and of the delivery 25 conduits leading therefrom may be varied as found best, the number of these conduits being preferably gradually increased from the first steam chamber to the last steam chamber, and the size or cross-sectional area 30 of the steam chambers 15', 16', 17', 18' and 19' and of the pipes 26, 27, 28, 29 and 30 being gradually increased in the order stated, in order to accommodate the enlarged volume of the expanding steam.

35 For the same reason the auxiliary motor wheel 32 is made of considerably greater length than that of the main motor wheel, the radial steam spaces 34 being of correspondingly greater length.

40 A water gage 39 will be usually employed for the boiler, as also a safety valve 40 and a steam gage 41 for the steam drum.

I claim:

1. In a steam motor, a rotary wheel having in its circumferential portion radial blades and intervening radial spaces, a casing closing said spaces upon the outside, pipes located at different points around the periphery and extending transversely of 45 said wheel, a steam generator having communication with both ends of the first of said pipes, the balance of said pipes having communication at both ends thereof with said radial spaces at different points around 50

the wheel, and delivery pipes from said 55 transverse pipes to the radial blades at different points around the wheel.

2. In a steam motor, a rotary wheel having in its circumferential portion radial blades and intervening radial spaces, a casing 60 closing said spaces upon the outside, pipes located at different points around the periphery and extending transversely of said wheel, a steam generator having communication with the first of said pipes, the balance of said pipes having communication 65 with said radial spaces at different points around the wheel, and a plurality of delivery pipes from each of said transverse pipes to the radial blades. 70

3. In a steam motor, a cylindrical casing, a rotary wheel in said casing having in its circumferential portion radial blades and intervening radial spaces, steam chambers of graduated capacity located at different 75 points around the periphery and extending axially of said casing, the first of said chambers having communication with a steam supply pipe and the other said chambers having communication with the radial 80 spaces of said wheel at different points around said casing, and delivery conduits of graduated capacity leading from said steam chambers to the spaces of said wheel at different points around the periphery of said 85 casing.

4. In a steam motor, a cylindrical casing, a rotary wheel in said casing having in its circumferential portion radial blades and intervening radial spaces, steam chambers of 90 graduated capacity located at different points around the periphery and extending axially of said casing, the first of said chambers having communication with a steam supply pipe and the other said chambers having 95 communication with the radial spaces of said wheel at different points around said casing, and series of progressively increasing numbers of delivery pipes leading from said steam chambers to the spaces of said wheel 100 at different points around the periphery of said casing.

In testimony whereof I affix my signature in presence of two witnesses.

ERNST WILLY SCHUSTER.
